MULTIPLE FUEL BURNER

Robert C. Vroom, Montclair, N. J., and David P. Graham, Flushing, N. Y., assignors to Peabody Engineering Corporation, New York, N. Y., a corporation of New York

Application May 29, 1942, Serial No. 444,956

5 Claims. (Cl. 110—22)

This invention relates to burners for liquid, gaseous and pulverized fuels, and has for its object to provide a new and improved burner of this type which is adapted to burn efficiently a variety of such fuels, either simultaneously or separately.

Another object of the invention is to provide a burner of the above type which is adapted to burn a variety of fuels differing in heat content, cleanliness, pressure, etc.

Another object is to provide a combination burner for a plurality of different fuels, employing a common air supply.

Another object is to provide a burner of the above type which is stable and efficient under all operating conditions.

Another object is to provide a burner of the above type having novel and improved details of construction and features of operation.

Various other objects and advantages will be apparent as the nature of the invention is more fully disclosed.

Although the novel features which are believed to be characteristic of this invention are pointed out more particularly in the claims appended hereto, the invention itself may be better understood by referring to the following description, taken in connection with the accompanying drawings forming a part thereof, in which a specific embodiment of the invention has been set forth for purposes of illustration.

In the drawings,

Fig. 1 is an end view of a burner embodying the present invention; and

Fig. 2 is a longitudinal sectional view thereof.

In the following description and in the claims certain specific terms have been used for convenience in referring to various details of the invention. These terms, however, are to be given as broad an interpretation as the state of the art will permit.

Referring to the drawings more in detail, the invention is shown as applied to a burner which is mounted in registration with a burner throat 11 in a furnace wall 12 forming part of a combustion chamber. The burner comprises a casing 10 having vertical front and rear walls 13 and 14 and a spiral or involute peripheral wall 15. The rear wall 14 is provided with an annular throat ring 16 which registers with the burner throat 11. The casing 10 is divided axially into an air chamber 17 and a fuel chamber 18 by means of a division plate 19 extending between the peripheral wall 15 and a central cylindrical burner tube 20, the forward (fireroom) end of which

communicates with an air register 21 and the rear (furnace) end of which is spaced from the throat ring 16 to provide an annular fuel passage 22 therebetween. The division plate 19 is shown as a helical plate, 360° in extent from its forward end 19a to its furnace end 19b, and these ends thereof, which are displaced axially, are joined by an axially extending plate 23. The air chamber 17 is provided with a rectangular air inlet passage 24 and the fuel chamber 18 is provided with a fuel inlet passage 25, shown as disposed peripherally, which extends the full axial and radial width of the fuel chamber 18 between the forward end 19a of the division plate 19 and the rear wall 14. By reason of the spiral peripheral wall 15 the cross sectional area of the fuel chamber for gas flow progressively decreases from the zone of fuel admission so as to equalize the gas flow through the annular fuel exit passage 22 around the entire burner throat. By making the division plate 19 helical as shown the fuel chamber 18 tapers in section both radially and axially and a square or nearly square cross-section is obtained, a shape which gives minimum pressure loss. In certain instances the division plate may be made flat instead of helical if the gas flow is found to have the required characteristics.

An annular wall 26 is attached to the throat ring 16 and to the rear wall 14 to form a second annular gas chamber 27 having a gas inlet passage 28 communicating therewith. An annular row of gas outlet ports 29 is provided in the throat ring 16 to discharge gas from the annular gas chamber 27 for combustion in the burner throat 11. The second annular gas chamber 27 may, of course, be made tubular or of other cross-sections and the gas discharge opening may be annular or of other form. Ports 29 have been shown merely as an illustration.

The burner is stiffened by radial struts 30 and 30a which extend respectively from the burner tube 20 and the wall 26 to the peripheral wall 15 in radial alignment with longitudinal stiffeners 31. The entire burner is supported by a frame 32. The portions of the casing forming the air chamber 17 may be provided with an insulating lining 10a. The walls of the gas chamber 18 may be similarly insulated if hot gases are to be supplied thereto. The air register 21 may be of any convenient type such as that disclosed in the Peabody Patent 1,628,424, dated May 10, 1927, and in the Leask et al. Patent 1,858,674, dated May 17, 1932, which includes a housing mounted on a front plate 35 and having a plurality of

peripheral air doors 36 adapted to receive air from the air chamber 17 for delivery through a suitable air discharge opening 37 into the fire-room end of burner tube 20. The register air doors 36 are adjusted by means of a suitable handle 38 on the front plate 35 of the register, and are adapted to control the rotation of the air supplied through the register to the burner tube 20. The insulated register front plate 35 may be mounted on the front wall 13 of the burner by bolts 38'. The particular form of air register, however, forms no part of the present invention and is accordingly not set forth in detail.

For the purpose of burning liquid fuel, the burner is provided with an atomizer barrel 40 which extends axially of the burner tube 20 and is provided at its inner end with an atomizer tip 41 and a diffuser 42 which are disposed adjacent the burner throat 11. The barrel 40 extends outwardly through the air register 21 and carries a coupling member 43 which is connected to the usual fuel supply pipes 44. The barrel 40 and tip 41 may be retracted when not in use.

The atomizer barrel may be of the type disclosed more in detail in Peabody Patent No. 1,628,424, above mentioned, and may comprise, for example, means for supplying liquid fuel under pressure to the atomizer tip and for discharging the same in a fine spray. The operating capacity may be varied by varying the supply pressure or by returning a portion of the fuel from the atomizer tip to the fuel pipe and controlling the pressure in the return line, as more fully described in the said patent.

The barrel 40 may also be designed to supply gaseous or pulverized fuel and may be used as an igniter or as an auxiliary fuel supply. If used only for initial ignition the barrel may be retracted after ignition has taken place. The diffuser 42 may also be retracted to a point near or at the furnace end of the burner tube 20 to control the direction of air and fuel flow to the burner throat.

Low B. t. u. gaseous fuels, such as blast furnace gas or producer gas, often contain moisture and suspended solid matter. When such gases are used as fuel in the chamber 18 a deposit or "mud" may form upon the outer periphery of burner tube 20, although the shape of the chamber providing uniform gas flow and the absence of pockets has been found to keep such deposits at a minimum. However, in order to remove any such deposit which may form, a steam ring 50 is positioned about the burner tube 20 in chamber 18 adjacent the division plate 19. This ring is shown as having a multiplicity of holes 51 for the discharge of steam about the tube 20 in a direction to blow off any deposit which may be formed thereon. The steam ring 50 is supplied at diametrically opposite points "X" and "Y" by a steam pipe 52 controlled by a valve 53. Steam blow means may also be provided for cleaning other surfaces of the fuel chamber 18. Suitable cleanout and inspection doors 54 are also provided in the peripheral wall 15. Of course, other fluid under pressure may be used instead of steam for blow off purposes if desired.

A fuel in suspension, such as pulverized coal, may be supplied to the interior of burner tube 20 through a conduit 55 which is connected to said tube substantially tangentially so that the pulverized fuel suspended in carrier air will enter the tube 20 tangentially and will rotate and advance about the inner peripheral wall thereof

to the burner throat, as shown more in detail in the Leask et al., patent above mentioned. The tube 20 may be provided with helical vanes 56 to direct the flow of fuel around the discharge end thereof at the burner throat. The conduit 55 passes through the peripheral wall 15 and the air chamber 17 in the dead air space between the air register 21 and the division plate 19b and therefore does not impede the flow of air through the air chamber 17 to the register 21.

In order to prevent gas leakage from the burner throat or furnace into the fire room, the throat is sealed by a metal cylinder 60 which also serves to support and retain the throat tile 61 and 62 and fits within the throat opening in the wall 12. A furnace plate 64 is secured over the front of the wall 12 and carries cylinders 65 and 66 which extend into the rows of bricks in the wall 12 around the throat opening.

Plate 64 projects radially inward at 67 to a slightly smaller diameter than the cylinder 66, almost into engagement with the tile support and sealing ring 66. An annular flange 68, carried by the cylinder 60, is clamped against the furnace plate 64 by bolts 69 which extend through brackets 34a attached to stiffeners 31. Packing 70 may be provided to form a tight seal between the flange 68 and the plate 64. Packing 71 may be inserted between the cylinder 66 and the sealing ring 66 and may be packed against the extension 67 of plate 64. The remaining space between the outside of the ring 60 and the wall bricks may be sealed by crushed firebrick or high temperature cement 71' which may be packed in after the burner is in place. Any gas which may leak radially through the throat tile is stopped by the ring 60. Gas leakage passages 72 are provided in the throat tile 61 at the furnace end of the ring 60 in order to permit leakage gas to pass freely into the furnace and to thus prevent the building up of pressure on the outside of the ring 60.

A plurality of tubes 75, extending from the gas chamber 18 through the wall 12 into the furnace, 45 may be spaced around the burner opening. These tubes supply fuel gas from the chamber 18 directly into the furnace and may be used for ignition or stabilization purposes. An annular space 73 is provided between the wall bricks and the plate 64 on the inside of the cylinder 65. Air under a pressure higher than the gas pressure is supplied thereto by a pipe 74. The air pressure in the space 73 assists further in causing any gas leakage to take place into the furnace. The tile 61 are made of smaller inside diameter than the tile 62 so as to avoid a forwardly facing shoulder which might be formed at the joint between these tile if they were made of the same diameter and were not exactly centered and would tend to impede gas flow.

A guide vane 80 may be mounted in the fuel chamber 18 between the furnace end 19b of the division plate 19 and the throat ring 16 and adjacent to the axial plate 23. This baffle 80 is shown as mounted on a rod 81 which extends through the front wall 13 and is provided with a handle 82. The baffle extends in an upwardly inclined direction to regulate the flow of fuel around the chamber 18. The baffle 80 is adjustable for effecting the desired control of fuel flow or may be omitted if not required.

A plurality of radial vanes 90 may be disposed in the passage 22 between the wall 14 and the burner tube 20. These vanes serve to stiffen the assembly and support the inner end of the burner

tube and also serve to direct and control the gas flow through the passage 22. The vanes may be angularly disposed if desired.

Operation

The above described burner is capable of burning a plurality of different fuels simultaneously and of operating efficiently when one or more of the fuels is shut off. For example, in certain plants coke oven gas may be available to supplement the blast furnace gas. The blast furnace gas being available at low pressure requires an admission chamber of substantial size. The chamber 18 is designed for this purpose and has a tapering flow area suited to obtain an even gas distribution around the burner throat. Other gas which may be at a higher pressure is supplied to the smaller annular chamber 27.

Pulverized fuel suspended in carrier air is supplied to the burner tube 20 and advances helically therein to the burner throat. Liquid fuel may be supplied through the atomizer barrel 40 and atomized in the burner throat from the tip 41 or gas or pulverized coal may be supplied axially of the burner according to the type of fuel available.

The present invention permits the burner to utilize gaseous fuel alone or in combination with liquid and pulverized fuels as required. The various fuels available at any particular plant may be used simultaneously and may be supplemented by other fuel as required. When operating with any desired fuel, or combination of fuels, the air doors 36 of register 21 are adjusted, by proper manipulation of the operating handle 38, to obtain the desired direction and speed of air flow to the burner throat 11. The combustion air, regulated by the pressure in the air chamber 17, flows through the burner tube 20 as a rotating mass and is mixed with the fuels under conditions adapted to produce an efficient mixture of air and fuels for combustion.

Although a specific embodiment of the invention has been shown for purposes of illustration, it is to be understood that various changes and modifications may be made therein as will be readily apparent to a person skilled in the art and certain parts, such as tubes 75, vane 80 and blades 90 may be omitted if desired.

What is claimed is:

1. A burner comprising a cylindrical burner tube open to a burner throat, an air register associated with the forward end of said tube remote from the burner throat to supply secondary air thereto, a spiral casing disposed about said burner tube and said air register and forming therewith an annular space of progressively decreasing radial width, a helical division plate extending between said casing and said tube and dividing said annular space into an air chamber open at its forward end to said air register and a fuel chamber of progressively decreasing radial and axial width having an annular opening around the periphery of the burner tube to the burner throat, a fuel supply duct communicating tangentially with said fuel chamber at its portion of greatest axial width, said fuel duct discharging into said chamber tangentially in the direction of decreasing cross-sectional area to cause fuel to be discharged axially through said annular opening to the burner throat, and an air supply duct supplying air to said air chamber for passage through said air register into said burner tube for mixing with the fuel at said throat.

2. A burner comprising a cylindrical burner

tube open to a burner throat, an air register associated with the forward end of said tube remote from the burner throat to supply secondary air thereto, a spiral casing disposed about said burner tube and said air register and forming therewith an annular space of progressively decreasing radial width, a helical division plate extending between said casing and said tube and dividing said annular space into an air chamber open at its forward end to said air register and a fuel chamber of progressively decreasing radial and axial width having an annular opening around the periphery of the burner tube to the burner throat, a fuel supply duct communicating tangentially with said fuel chamber at its portion of greatest axial width, said fuel duct discharging into said chamber tangentially in the direction of decreasing cross-sectional area to cause fuel to be discharged axially through said annular opening to the burner throat, an air supply duct supplying air to said air chamber for passage through said air register into said burner tube for mixing with the fuel at said throat, and a second fuel supply duct extending through said casing and through said air chamber and discharging tangentially into said burner tube at about the location of greatest axial tube length on the air chamber side of said division plate to supply a second fuel to the inside of said tube.

3. A burner comprising a cylindrical burner tube open to a burner throat, an air register associated with the forward end of said tube remote from the burner throat to supply secondary air thereto, a spiral casing disposed about said burner tube and said air register and forming therewith an annular space of progressively decreasing radial width, a helical division plate extending between said casing and said tube and dividing said annular space into an air chamber open at its forward end to said air register and a fuel chamber of progressively decreasing radial and axial width having an annular opening around the periphery of the burner tube to the burner throat, a fuel supply duct communicating tangentially with said fuel chamber at its portion of greatest axial width, said fuel duct discharging into said chamber tangentially in the direction of decreasing cross-sectional area to cause fuel to be discharged axially through said annular opening to the burner throat, an air supply duct supplying air to said air chamber for passage through said air register into said burner tube for mixing with the fuel at said throat, a second fuel supply duct extending through said casing and through said air chamber and discharging tangentially into said burner tube at about the location of greatest axial tube length on the air chamber side of said division plate to supply a second fuel to the inside of said tube, and a fuel ring around and spaced from the end of said burner tube to form said annular opening from said first fuel chamber, said fuel ring having orifices to supply a third fuel for mixing with the secondary air from said burner tube at the burner throat.

4. A burner comprising a cylindrical burner tube open to a burner throat, an air register associated with the forward end of said tube remote from the burner throat to supply secondary air thereto, a spiral casing disposed about said burner tube and said air register and forming therewith an annular space of progressively decreasing radial width, a helical division plate extending between said casing and said tube and dividing said

annular space into an air chamber open at its forward end to said air register and a fuel chamber of progressively decreasing radial and axial width having an annular opening around the periphery of the burner tube to the burner throat, a fuel supply duct communicating tangentially with said fuel chamber at its portion of greatest axial width, said fuel duct discharging into said chamber tangentially in the direction of decreasing cross-sectional area to cause fuel to be discharged axially through said annular opening to the burner throat, an air supply duct supplying air to said air chamber for passage through said air register into said burner tube for mixing with the fuel at said throat, peripherally spaced longitudinal stiffeners reinforcing said casing and radial stiffeners attached to said longitudinal stiffeners and extending between said burner tube and said casing.

5. A burner comprising a cylindrical burner tube open to a burner throat, an air register associated with the forward end of said tube remote from the burner throat to supply secondary air thereto, a spiral casing disposed about said burner tube and said air register and forming therewith an annular space of progressively decreasing ra-

5 dial width, a helical division plate extending between said casing and said tube and dividing said annular space into an air chamber open at its forward end to said air register and a fuel chamber of progressively decreasing radial and axial width having an annular opening around the periphery of the burner tube to the burner throat, a fuel supply duct communicating tangentially with said fuel chamber at its portion of greatest axial width, said fuel duct discharging into said chamber tangentially in the direction of decreasing cross sectional area to cause fuel to be discharged axially through said annular opening to the burner throat, and an air supply duct supplying air to said air chamber for passage through said air register into said burner tube for mixing with the fuel at said throat, a fluid manifold around said burner tube on the fuel chamber side of said division plate having openings disposed to blow off accumulations from the surface of said tube and connections to supply fluid under pressure to said manifold.
